OF SAN FRANCISCO, CALIFORNIA

BRAKING MECHANISM FOR YIELDING HIGHWAY BARRIERS

Application filed June 4, 1932. Serial No. 615,453.

This invention relates to improvements in braking mechanism for yielding highway barriers.

The principal object of the invention is to provide means whereby highway barriers will be free to pay out a considerable distance during the time that the barrier is descending if the same is struck by a moving vehicle, and further to provide means whereby this paying out of the barrier will be retarded in its action as soon as the barrier has reached its lower-most position.

A further object is to provide means whereby the retarded paying out action is progressively resisted as the paying out operation progresses.

A further object is to provide means whereby the barrier may be retracted after being payed out.

A further object is to produce a device which is economical to manufacture.

Other objects and advantages will be apparent during the course of the following description.

In the accompanying drawings forming a part of this specification and in which like numerals are employed to designate like parts throughout the same,

Fig. 1 is a front elevation of a barrier having my invention attached thereto, the supporting columns being shown in dotted lines,

Fig. 2 is an enlarged detail front elevation of one of the barrier braking mechanisms,

Fig. 3 is a fragmentary cross sectional view taken on the line 3—3 of Fig. 2, and

Fig. 4 is a top plan view of Fig. 3 partly in cross section and showing the magnetic valve and control therefor.

Barriers are placed adjacent all bridges wherein a section of the bridge is adapted to be opened for traffic therethrough during which time traffic over the bridge is temporarily stopped. These barriers are all different types, the type to which my invention applies is the vertically lifting flexible barrier type wherein a net is suspended between two posts positioned at opposite sides of the highway, the ends of the net being secured to cables which are mounted in travellers movable in the supports. As the barrier and

supports form no part of this invention they will only be incidentally referred to.

My invention consists of a hydraulic cylinder 5 supported on the carrier 6. A piston 7 is movable in the cylinder 5 and has a tubular connecting rod 8 which is secured by nuts 9 to the top plate 11 of the carrier 6. Mounted upon the sides of the carrier 6 are guide supports 12 and 13 which support the ends of the cables 14 and 16, respectively, of the barrier 17. These cables 14 and 16 pass over idlers 18 and 19, respectively, and are then lead over pulleys 21 and 22. The pulleys 21 are mounted upon the top of the carrier 6 while the pulleys 22 are mounted upon the bottom of the cylinder 5.

The result of this construction is that when the barrier is struck, the cables 14 and 16 will cause the cylinder 5 to rise upon the connecting rod 8 thus permitting the cables to pay out the necessary distance to perform the function desired.

Referring now to Fig. 3, it will be noted that the cylinder 5 has a by-pass passage 23 which extends the entire length of the cylinder and that ports 24 are spaced from end to end of the cylinder, which ports are partially closed through the medium of tapered valves 26 the purpose of which will be later shown. The piston 7 has ports 27 formed therethrough, the purpose of which will be later seen. A rotary valve 28 is secured to a rod 29 extending through the connecting rod 8 and is also provided with ports 29 which ports are adapted to be moved into alignment with the ports 27. This rod 29 is supported by an expansion spring 31 which has its lower end abutting a collar 32 supported within the connecting rod 8 and has its upper end abutting a nut 33. A lever 34 is held between the nut 33 and the nut 36. A spring 37 is connected to the lever 34 and to a pin 38 secured at the side of the cylinder 5. This spring tends to normally hold the rod 29 in such a position that the ports 27 and 29 will be out of alignment. An electromagnet 39 is attached to the lever 34 which electromagnet is connected to the line wires L1 and L2 through the medium of a bridge bolt 41 engaging contacts 42 and 43.

The result of this construction is that when my device is installed and connected with the bridge mechanism, the initial operation of the bridge mechanism will cause the carriers 6 to descend toward the highway thus lowering the barrier in the same direction. During the period of descent the electromagnet 39 being energized, the ports 27 and 29 will be in alignment with each other and therefore should a vehicle strike the barrier during the time it is descending, the vehicle will cause the cables to pay out with the movement of the vehicle, which paying out movement will not be resisted materially for the reason that a fluid confined within the cylinder will pass through the ports 27 and 29' as the cylinder is moved upwardly over the piston through the action of the paying out of the cables 14 and 16, thus drawing upon the reserve portion of the cables extending over the pulleys 21 and 22.

It is obvious that in all probabilities, the driver of a vehicle striking the barrier under these conditions would stop his vehicle and drive backward with the result that the release of pressure from the barrier will permit the cylinder 5 to drop, thus taking up substantially all of the slack in the barrier supporting cables.

Assuming now that the carriers reach the bottom of their travel without a vehicle striking, then the interlocking mechanism connecting with the bridge permits the operator of the bridge to withdraw the locking bolt 41 so that the bridge may be raised, which act disconnects the contacts 42 and 43, thus de-energizing the electromagnet 39 with the result that the spring 37 will rotate the rod 29 thus rotating the valve 28 so as to move the ports 27 and 29 out of alignment with each other. Now should a vehicle strike the barrier the same paying out action will take place with the exception that as the cylinder rises on the piston, fluid within the piston, in order to escape to a point above the piston, must pass through the ports 24 and into the by-pass 23 thence into the upper portion of the cylinder, and during the initial upward movement it will be obvious that all of the ports 24 will permit this by-pass action, but during the later movement it will be obvious that as the piston passes the various ports their action will be cut off, thus gradually increasing the hydraulic resistance to the cylinder moving over the piston and as a result the stopping action of the vehicle engaging the barrier when it is in its lower-most position will be gradual thus preventing injury, to the vehicle or to the occupant, but providing a very effective stopping medium.

After pressure is relieved from the barrier the cylinder 5 will again tend to move to its lower-most position, which movement would be slow were it not for the fact that

the valve 28 may move away from the piston 7 as indicated in dotted lines in Fig. 3 thus permitting the fluid above the piston to rapidly flow to a point below the piston. As soon as the cylinder has reached the bottom of its travel the spring 31 will again raise the valve 28 into contact with the bottom of the piston.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In combination with a highway barrier capable of being moved to an operative and inoperative position, of a hydraulic braking mechanism associated with the barrier and connected to said barrier when in operative and inoperative position and serving to retard movement of the barrier in a horizontal direction.

2. In a device of the character described, a pair of spaced posts and a flexible barrier therebetween defining a highway barrier, hydraulic braking mechanism associated with the posts and connected to said barrier while said barrier is in both operative and inoperative positions and adapted when in an operative position to retard horizontal movement of a vehicle contacting the flexible barrier, and means embodied in said mechanism for releasing the retarding action of the hydraulic braking mechanism when the barrier is in an inoperative position.

3. In combination with a highway barrier capable of being moved into operative and inoperative position, a brake mechanism comprising a cylinder, a piston movable in said cylinder, said cylinder and said piston being operatively connected to said barrier when said barrier is in either operative or inoperative position, a by-pass formed on said cylinder, valves connecting said cylinder and said by-pass whereby movement of said piston in said cylinder will be progressively increasingly retarded to retard movement of said barrier when said barrier is in operative position.

4. In combination with a highway barrier capable of being moved into operative and inoperative position, a brake mechanism comprising a cylinder, a piston movable in said cylinder, said cylinder and said piston being operatively connected to said barrier, a by-pass formed on said cylinder, valves connecting said cylinder and said by-pass whereby movement of said piston in said cylinder will be progressively increasingly retarded to retard movement of said barrier when said barrier is in operative position, and a valve

mounted on said piston, said piston and said valve having ports therein whereby when said ports are in alignment the retarding action of said device will be prevented.

- 5 5. A hydraulic braking mechanism for a highway barrier, including in combination with a barrier and cables therefor, of a cylinder, a piston, cable carrying means carried by said cylinder and said piston and capable of having the cables of said barrier reaved thereover, said piston having ports formed therein, a valve movably contacting one side of said piston, ports formed in said valve, means for movably holding said ports in said piston and said valve out of registration, means for moving said ports into registration, and yielding means for supporting said valve in contact with said piston.
- 10 6. A hydraulic braking mechanism for a highway barrier including in combination with a barrier and cables therefor, of a cylinder, a piston, a connecting rod, cables carrying means connected to said cylinder and to said connecting rod, said piston having ports formed therein, a valve normally engaging one face of said piston, ports formed in said valve, the ports in said valve and said piston being capable of registration, a rod connected to said valve whereby said valve may be rotated with respect to said piston, resilient means for supporting said rod whereby said valve is normally held against said piston, resilient means for normally preventing registration of said ports in said valve and said ports in said piston, and remote control means for rotating said valve against said last mentioned resilient means, whereby said ports in said valve are moved into registration with said ports in said piston.
